DENTAL CLEANING COMPACT

Will O. Smith and Elizabeth E. Smith,
Pittsburgh, Pa.

Application August 29, 1938, Serial No. 227,403

4 Claims. (Cl. 132—84)

This invention relates to toothbrushes, and its general object is to provide what may be termed a dental cleaning compact that includes a toothbrush, dentifrice container, and a holder therefor, all connected together in a single unit, the holder and brush being foldably associated in a manner for ready disposal of the brush into and out of use and the holder provides a housing for the brush and for the container, so as to retain the same free from dirt, dust or contamination from other foreign matter, and therefore in a clean and sanitary condition.

A further object is to provide a dentifrice cleaning compact in which the brush thereof is pivotally connected to the holder and is spring pressed to be urged and held in open position for use when released from the holder.

Another object is to provide a dental cleaning compact in which the dentifrice container is slidably mounted in the holder for disposal into and out of the path of the bristles of the brush, to receive the bristles when in the path thereof for the dentifrice to adhere thereto, and to allow the brush to snugly fit within the holder when the container is out of said path.

A still further object is to provide a dental toilet article of the character set forth, that can be folded in a very compact form and retained accordingly, so that it can be conveniently carried in the purse or vest pocket of the user.

A further object is to provide a dental cleaning compact that is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a longitudinal sectional view taken through the article which forms the subject matter of the present invention, in folded position.

Figure 2 is a longitudinal sectional view, with parts in elevation, and illustrates the brush extended for use in full lines and the manner of applying the dentifrice thereto in dotted lines.

Figure 3 is a top plan view of the article in open position, with parts in section.

Figure 4 is a sectional view taken approximate-

ly on line 4—4 of Figure 1, looking in the direction of the arrows.

Referring to the drawing in detail, it will be noted that the holder of our article is shown as being of tubular formation and is made up of a lower body section 1 and an upper cover section 2, both being of substantially semi-circular channel formation and of the same length, but the body section 1 is of greater cross sectional area than the section 2 and of less diameter, in order to receive the section 2 with its side edge portions in overlapped association with the side edge portions of the section 1, as best shown in Figure 4, and to set up a frictional engagement therewith to hold the cover section in closed position, as will be apparent.

It will be obvious that the holder provides a housing, and one of the ends thereof is closed by a wall made up of sections 3 and 4 formed respectively with the upper and lower channel sections, and the wall sections are hingedly secured together for connecting the channel sections accordingly, as clearly shown in Figures 1 and 2. The opposite end of the holder or housing is closed by a substantially cylindrical shaped block 5 that is fixed in the channel of the body section and extends above the same for arrangement in the path of the cover section to receive the same for fitting association therewith, when the cover section is disposed in closed position, as best shown in Figure 4.

The outer portion of the block 5 is slotted as at 6 and pivotally mounted in the slot by a pin 7 is the reduced end 8 of the handle or shank 9 of the toothbrush 10, the latter including a head of any suitable shape with bristles 11 fixed therein. The pivotal connection of the toothbrush with respect to the housing allows the same to be moved into and out of the housing when the cover section 2 is in open position, as shown, but there is preferably provided a coil spring 12 surrounding the pin 7, with its end convolutions engaged with the reduced end 8 and the block respectively, as best shown in Figure 3, to urge and hold the brush to open position, when released from the housing or holder, and it will be obvious that the brush is released when the cover section 2 is moved to open position.

The dentifrice container is in the form of a tray that includes a body 13 shaped to fit the lower or body section 1 for slidable movement therein, and is retained accordingly, by the inturned upper edges of the body section, and which provide tongues 14 disposed in overlapped relation with the upper edges of the body 13 of the tray. The

tray is provided with a cover in the form of a lid 15 that has one end hingedly secured to one end wall of the body 13 and the opposite end has a latch hook 16 formed thereon for engagement with the opposite wall of the body 13 for holding the lid 15 in closed position, as will be apparent upon inspection of Figure 1.

It is believed that the use of our dental cleaning compact will be obvious from the foregoing description and the disclosure in the drawing, but it might be mentioned that when it is desired to use the same, the upper cover section 2 is moved to its open position as best shown in Figure 2, which releases the brush for movement thereof to its full line position of that figure. The dentifrice container is then moved from its normal position of Figure 1 to that of Figure 2 for disposal in the path of the bristles to receive the same when the lid 15 is in open position, for the application of the dentifrice to the bristles, when the brush is moved to the dotted line position of Figure 2. The brush is then released, thence the lid 15 and cover section 2 are moved to closed position, and the housing or holder is then gripped and the brush applied to the teeth in the usual manner, as it is obvious that the holder or housing cooperates with the shank in providing a handle for the brush.

It will be further obvious that the parts of our article may be made from any material suitable for the purpose, and that any kind of dentifrice can be used and applied within the container, such as powder, paste or the like. The article can be made in various sizes, but when folded as shown in Figure 1, is very compact and will take up minimum space, so that it can be readily and conveniently carried in the purse or vest pocket of the user.

It is thought from the foregoing description that the advantages and novel features of the invention will be readily apparent.

It is to be understood that changes may be made in the construction and in the combination and arrangement of the several parts, provided that such changes fall within the scope of the appended claims.

What we claim is:

1. A dental cleaning compact comprising a tubular holder including companion body and cover channel shaped sections hinged together at one end for movement of the cover section in overlapped association with the body section to provide a housing, a brush pivotally secured to the holder for movement into and out of the same,

and a dentifrice container shaped to fit the body section and slidably mounted therein for movement into and out of the path of the brush.

2. A dental cleaning compact comprising a tubular holder including companion body and cover channel shaped sections hinged together at one end for movement of the cover section in overlapped association with the body section to provide a housing, a spring pressed brush pivotally secured to the opposite end of the body section for movement into and out of the holder, said brush being held within the holder by the cover section when the latter is in closed position and urged and held out of the holder by the spring of the brush when the cover section is moved to open position, and a dentifrice container slidably mounted in the holder for movement into and out of the path of the brush.

3. A dental cleaning compact comprising a tubular holder including companion body and cover channel shaped sections hinged together at one end for movement of the cover section in frictional overlapped connection with the body section for securing the cover section thereto in closed position, a block secured to the opposite end of the body section, a brush including a shank pivotally secured to the block for movement into and out of the holder, a spring engaged with the block and shank for urging and holding the brush out of the holder in position for use, said brush being held within the holder by the cover section when the latter is in closed position, and a dentifrice container slidably mounted in the holder for movement into and out of the path of the brush.

4. A dental cleaning compact comprising a tubular holder including companion body and cover channel shaped sections hinged together at one end for movement of the cover section in frictional overlapped connection with the body section for securing the cover section thereto, a brush pivotally secured to the opposite end of the holder for movement into the holder to be housed thereby and out of the same to a position for use when the cover section is in open position, a dentifrice container including a tray shaped to fit the body section and slidably mounted therein for movement into and out of the path of the brush, inwardly directed tongues formed on the side edges of the body section and overlapping the tray to hold the latter within the body section, a hinged closure for the tray, and a latching tongue for holding the closure in closed position.

WILL O. SMITH.
ELIZABETH E. SMITH.
